AUTOMOBILE DOOR LOCK KNOB

Richard Perfit, Roslyn Heights, N.Y., assignor to Abilene
Associates Inc., Roslyn Heights, N.Y., a corporation
of New York

Filed Sept. 22, 1967, Ser. No. 8,688

Term of patent 14 years

(Cl. D50—7)

FIGURE 1 is an elevational view of an automobile door lock knob embodying my new design;

FIGURE 2 is an elevational view of FIGURE 1 rotated 90°;

FIGURE 3 is an elevational view showing the side opposite that seen in FIGURE 1;

FIGURE 4 is a top plan view thereof.

I claim:

The ornamental design for an automobile door lock knob, substantially as shown.
